UNITED STATES PATENT OFFICE.

CHRISTIAN E. LANSTRUM, OF GALESBURG, ILLINOIS.

SPRAYING DEVICE.

SPECIFICATION forming part of Letters Patent No. 696,057, dated March 25, 1902.

Application filed March 16, 1901. Serial No. 51,534. (No model.)

To all whom it may concern:

Be it known that I, CHRISTIAN E. LANSTRUM, a citizen of the United States, residing at Galesburg, in the county of Knox and State of Illinois, have invented certain new and useful Improvements in Spraying Devices; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

One object of this invention is to provide a device which will cheaply and readily moisten and cool vegetables, fruits, and flowers.

A further object is that the device shall generally be placed in a location in front of the place of business of grocers, florists, marketmen, and dealers in vegetables or flowers.

A further object of this invention is to provide a device whereby refrigeration may be readily and cheaply maintained in houses, 25 sick-rooms, hospitals, and the like.

A further object of the invention is to provide a device whereby an equable or uniform temperature may be maintained in greenhouses or conservatories.

30 Further objects of the invention will hereinafter appear.

In the drawings, Figure 1 is a perspective view showing my improved spraying device as it appears in operation, also showing a water-supply pipe and a valve connected therewith. Fig. 2 is a section in the line 2 2 in Fig. 1 seen from the direction indicated by the arrows, and Fig. 3 is a section in the line 3 3 seen from the direction of the arrows.

40 The invention consists, primarily, in a disk or plate A, supported by posts B, which posts are in turn supported by a lower disk or plate C. Through the intermediate or central part of the disk C is a tube or pipe D.

45 It is to be understood that the plate or disk may be dispensed with and that the posts

B and disk A may be supported by a wheel or ring (not shown) or in any desired or preferred manner.

Preferably the tube D is made integral with 50 the disk C, but may be threaded therethrough and thereafter screw-threaded on the part D' (see Fig. 2) to fit a water-pipe connection from either a city water service or an elevated tank. 55

If preferred, the part C may be seated loosely on a shoulder C' on the water-supply pipe. In such case radially-curved ledges (not shown) are formed on the lower surface of the disk A. By reason of these radially-curved 60 ledges the force of the stream of water impinging thereagainst will cause the parts A, B, and C to revolve, and thus throw the mist or spray in a circular direction.

Through the center of the tube or pipe D 65 and extending throughout its length is an orifice or nozzle E.

In operation the device is attached to a water-supply pipe F. The water being thrown from its source upwardly will impinge against 70 the plate or disk A, and thereby create a fine spray or mist.

By the use of this invention the mist created by it will, by reason of evaporation, cause a low degree of temperature, which will cool 75 and preserve vegetables, fruits, meats, or other articles which are placed thereunder. If placed in a room, it will suffice to reduce the temperature in warm weather several degrees in a very few minutes and to a lesser 80 degree than could be produced by the use of ice. When used in conservatories or greenhouses, it will be readily understood that the temperature may be regulated by the amount of water which is allowed to escape from the 85 orifice E and to impinge against the disk A.

A well-known fact is that grocers, florists, and marketmen display in front of their places of business during warm weather vegetables, flowers, fruits, and the like and that all these 90 are often subjected to a high degree of temperature. It is thought that no device has

heretofore been provided which will with so small expense save dealers from loss caused by warm weather.

- Having thus fully described my invention, 5 what I claim as new is—
1. In combination, an upper plate or disk A, a lower plate or disk C, a tube or pipe D, having a discharge-opening E, as and for the purposes described.
  - 10 2. In combination, an upper plate or disk

A, a lower plate or disk C, a discharge-opening through said disk C, and posts connecting said disks, substantially as and for the purpose described.

In testimony whereof I affix my signature 15 in presence of two witnesses.

CHRISTIAN E. LANSTRUM.

G. A. SANTURG.

Correction in Letters Patent No. 696,057.

It is hereby certified that in Letters Patent No. 696,057, granted March 25, 1902, upon the application of Christian E. Lanstrum, of Galesburg, Illinois, for an improvement in "Spraying Devices," an error appears in the printed specification requiring the following correction, viz: On page 1, in line 45, after the word "disk" the reference letter *C* should be inserted; and that the said Letters Patent should be read with this correction therein that the same may conform to the record of the case in the Patent Office.

Signed, countersigned, and sealed this 8th day of April, A. D., 1902.

[SEAL.]

F. L. CAMPBELL,
Assistant Secretary of the Interior.

Countersigned:

F. I. ALLEN,
Commissioner of Patents.
